UNITED STATES PATENT OFFICE.

BERT W. PARKER, OF NEW YORK, N. Y.

GARTER.

1,066,524.

Specification of Letters Patent.

Patented July 8, 1913.

Application filed May 9, 1912. Serial No. 696,079.

To all whom it may concern:

Be it known that I, BERT W. PARKER, a citizen of the United States, residing in the city, county, and State of New York have invented a new and useful Improvement in Garters; and I do hereby declare that the following is a full, clear, and exact description of the same.

My invention has reference to an improvement in garters particularly intended for supporting men's socks and of the class in which a clasp to catch the upper edge of the sock is suspended from an adjustable band which encircles the calf of the leg.

15 In one well-known example of a garter of this kind, the clasp is suspended from a cord loop, one side of which plays loosely through the looped end of an elastic tape, and the other through a flat hook on the 20 other end of the elastic tape, the loop of the elastic tape being shortened or lengthened by means of an adjustable buckle to adjust the garter to the size and length of the 25 wearer's leg. In this type of garter, the rubber of the elastic tape, embracing the warm upper part of the leg, soon stretches and deteriorates so as to be useless, and further unpleasantly binds the leg, while the 30 cord is also uncomfortable and soon wears out particularly because of its constant playing through the hook and loop of the elastic tape. In another type of this class of 35 garter, the clasp is suspended from a roughly triangular pad, which is permanently fastened to one end of the adjustable elastic tape and by a detachable fastening to the adjustable loop on the other end of the elastic tape. This pad is clumsy, unsightly, 40 hot and unsanitary.

45 In my improved garter, I make the adjustable band which embraces the calf, preferably of inelastic tape which is continued downward on one side of the sock clasp and carried upward therefrom on the other side 50 of a V to a detachable fastening to which the other end of the inelastic tape is secured. From this detachable fastening a short strap 55 of elastic tape is carried transversely across the lower part of the leg to a permanent union with the other side of the suspension V formed by the inelastic tape, thus forming an open suspension triangle, which will readily adapt itself to any size and length of leg, thereby forming a garter which will be free from the objections hereinbefore mentioned in other forms of garters and

will have other advantages hereafter set forth.

In order that my invention may be fully understood, I shall first describe in detail 60 the mode in which I carry my invention into practice and then distinctly claim the invention.

Reference is to be had to the accompanying drawings forming part of this specification in which like parts are designated by the same letters in both figures.

Figure I represents a garter embodying my invention, detached. Fig. II represents the same in use.

70 In the manufacture of this embodiment of my invention, I make the leg band of inelastic tape, 10, and by preference of flat tubular fabric for strength and durability. In the case of the single clasp garter shown, 75 I prefer to continue the clasp end of the inelastic tape 10, downward on one side of a V-shaped pendant to the sock clasp 11, which may be of any suitable form as that shown, and then after attaching the vertex 80 of the V-pendant to the clasp 11, continue the inelastic tape upward on the other side of the V, to the point of attachment to the free end 12 of the inelastic tape 10.

75 For attaching the free end 12 of the elastic tape to the pendant, any suitable form of coupling may be used. For example, I have here shown an ordinary metal loop 13, carried loosely on the looped free end 12 of the tape 10, which latter is adjustable to fit 90 the leg by means of an ordinary adjustable buckle 14. The metal loop 13 is adapted to engage detachably, a headed post 15 on the V-pendant.

95 To give all needed elasticity to the inelastic tape 10 where it embraces the leg, I extend a rubber web or other suitable elastic strap 16 across the top of the V-pendant, attaching the respective ends of the strap to the inelastic tape on opposite sides of the V- 100 pendant. This elastic strap 16 gives to permit the inelastic leg band to adapt and adjust itself to the length, size and shape of the leg, the opposite tape sides of the open clasp pendant separating and approaching 105 to permit the necessary extension and contraction of the elastic strap 16. At the same time the flat strap and flat tape sides of the clasp pendant lie comfortably on the leg without interfering with the necessary 110 coolness and ventilation thereof. The inelastic tape 10 not only slides more freely

through the adjusting buckle 14 than the usual elastic band, but will not rapidly deteriorate as rubber tape does in the same location on the upper and under warm part 5 of the leg. The inelastic tape 10 also does not uncomfortably bind and disfigure the leg as does the usual rubber tape and is much stronger and durable than rubber tape. At the same time the elastic cross-strap 16, 10 gives all needed elasticity to the garter, and being only on the lower, forward and cool part of the leg, does not deteriorate from the heat and perspiration of the leg. Further, there being only a short piece of elastic tape required for the cross-strap, it can be made of the very best rubber fabric without as much expense as is ordinarily required to make the leg band of inferior elastic fabric.

20 In fastening the ends of the elastic strap 16 to the elastic tape when the latter is made of flat tubular fabric, I usually prefer to slit the side of the tubular tape 10 and insert and stitch the ends of the strap 16 therein 25 as indicated. At the same time, I may fasten the coupling post 15 to the union of the strap 16 and tape 10, by inserting arms 17 on the bottom of the post 15 between the strap fabric and upper tape fabric, and 30 stitching the post arms therebetween as indicated.

It is evident that two sock clasps instead of one as shown may in some cases be used with this form of garter by separating the 35 tape 10 at the vertex of the V-pendant and attaching a clasp to each of the separated pendant ends of the tape.

Having thus described my invention and the mode in which I carry the same into 40 practice, what I claim is:

1. A garter formed of separated depending tapes converging at the bottom to form a V with a sock clasp at the vertex, an elastic cross-strap having its ends attached to 45 the respective upper ends of the converging depending tapes, an adjustable inelastic leg band extending from one end of the elastic cross-strap and having its other end provided with a coupling for attaching it to the 50 other end of the elastic cross strap, substantially as described.

2. A garter consisting of a sock clasp, a

leg band formed of inelastic tape extending downward on one side to the sock clasp and upward therefrom to form a V-like pendant, 55 an elastic cross-strap having its ends attached to the members of the pendant at a substantial distance above the clasp, and a coupling for attaching the free end of the inelastic leg band to the union of the elastic 60 cross-strap and the free upper end of the V-like clasp pendant, substantially as described.

3. A garter consisting of a sock-clasp, a leg band formed of inelastic tubular tape 65 extending downward on one side to the sock clasp and upward therefrom to form a V-like clasp pendant, an elastic cross-strap connecting the upper ends of the V-like clasp pendant and having its ends inserted through 70 slits and stitched inside the inelastic tubular tape, and a coupling for attaching the free end of the inelastic leg band to the union of the elastic cross-strap and the free upper end of the V-like clasp pendant, substan- 75 tially as described.

4. A garter formed of separated depending tapes converging at the bottom to form a V with a sock clasp at the vertex, an elastic cross-strap having its ends attached to 80 the respective upper ends of the converging depending tapes, an adjustable leg band extending from one end of the elastic cross-strap and having its other end provided with a coupling for attaching it to the other 85 end of the elastic cross strap, substantially as described.

5. A garter formed of separated inelastic depending tapes converging at the bottom to form a V with a sock clasp at the vertex, 90 an elastic cross strap having its ends attached to the respective upper ends of the converging depending tapes, an adjustable leg band extending from one end of the elastic cross-strap and having its other end provided with a coupling for attaching it to the other 95 end of the elastic cross-strap, substantially as described.

In testimony whereof I have hereunto set my hand the 29th day of April 1912.

BERT W. PARKER.
